EXPANSIBLE LINK CHAIN FOR A BRACELET
OR THE LIKE

Walter Krust, Brooklyn, N. Y., assignor to Jacoby-Bender, Inc., New York, N. Y., a corporation of New York

Application July 5, 1952, Serial No. 20,474

Term of patent 7 years

(Cl. D45—4)

To all whom it may concern:

Be known that I, Walter Krust, a citizen of the United States and a resident of Brooklyn, county and State of New York, have invented a new, original, and ornamental Design for an Expansible Link Chain for a Bracelet or the like, of which the following is a specification, reference being had to the accompanying drawing, forming a part thereof, in which:

Fig. 1 is a top plan view of the expansible link chain showing my new design in contracted condition, the conventional bottom links being shown in broken lines;

Fig. 2 is a top plan view thereof in partially expanded condition, portions of the conventional bottom links being visible between the top links;

Fig. 3 is a side elevational view of one of the individual top links of the chain of Fig. 1; and

Fig. 4 is an end elevational view of the individual top link of Fig. 3.

The central portion of each of the top links is defined by a sheet of leather or the like visible through an opening in the opaque top links, specific leather markings being indicated in broken lines.

The essential features of my design reside in those portions shown in full lines.

I claim:

The ornamental design for an expansible link chain for a bracelet or the like, as shown and described.

WALTER KRUST.
